UNITED STATES PATENT OFFICE.

GLENN H. CURTISS AND WILLIAM L. GILMORE, OF GARDEN CITY, NEW YORK, ASSIGNEES TO CURTISS AEROPLANE AND MOTOR CORPORATION, A CORPORATION OF NEW YORK.

HULL FOR FLYING-BOATS.

1,294,414.

Specification of Letters Patent. Patented Feb. 18, 1919.

Application filed March 13, 1918. Serial No. 222,211.

To all whom it may concern:

Be it known that we, GLENN H. CURTISS and WILLIAM L. GILMORE, citizens of the United States, residing at Garden City, in the county of Nassau and State of New York, have invented certain new and useful Improvements in Hulls for Flying-Boats, of which the following is a specification.

Our invention relates to flotation bodies which in many respects may be likened to both the hull of a flying boat and the pontoon of a hydro-aeroplane. It is characterized by an arrangement of interior frame parts which render it particularly adaptable to that type of flying boat in which the motor unit is inclosed within the boat body. The engine bed beams or supports extend longitudinally substantially the full length of the hull and function conjointly as structural elements or stringers thereof. In this way the motor vibrational strains are effectively distributed as well as the enormous weight of the motor itself. The beam of the boat is widened to such an extent that it is extremely seaworthy even in the roughest seas. The bottom of the boat is constructed in hydroplane form and in cross section is somewhat more acutely V-shaped than heretofore.

Fin excrescences extend out laterally in direct continuation of the boat bottom throughout its full length. The fins however are not of a uniform width. They emanate from the extreme bow and widen out gradually to a point substantially amidships where they commence to decrease in width gradually so as to intersect at the stern. In this way the hull is strengthened longitudinally and its displacement per unit of length materially increased. Moreover, the hull is streamlined more effectually.

The bow of the boat is more or less a cross between the scow and cut-water types. The bottom is longitudinally salient or convexed and provided with two rearwardly facing steps which are built-on rather than built-in as heretofore. These two steps are located nearer the rear end of the hull than the forward end, the forward step lying substantially beneath the center of gravity. By providing two steps arranged in tandem suction and skin friction are minimized and the craft enabled to come quickly to a hy-

dropianing position. This permits of aerial flight without a long preliminary run on the water.

Of the drawings:

Figure 1 is a top plan view of the flotation body showing more or less diagrammatically the shape of the hull and fins in plan.

Fig. 2 is a side elevation of the flotation body as illustrated in Fig. 1.

Fig. 3 is a front end elevation.

Fig. 4 is an enlarged longitudinal vertical sectional view showing the interior construction of the fore part of the hull.

Fig. 5 is a similar view showing the interior construction of the after part of the hull. (This figure is a continuation of Fig. 4.)

Fig. 6 is a transverse section on the line 6—6, Fig. 1, and

Fig. 7 is a transverse section on the line 7—7, Fig. 1.

In Fig. 1 it will be noted that the flotation body or hull is pointed both fore and aft and that its shape in plan is symmetrical or nearly symmetrical about a line intersecting it at an amidships point. In elevation the bow end is more or less blunt as is also the stern end although the generating lines which emanate from the stern end meet at the stem to improve the streamline at this point. Such construction gives us a relatively blunt entering portion and a gradually tapering tail portion which is best. The fore part of the hull is designated as an entirety by the numeral 10. It is provided with a bow cockpit 11 for an observer or passenger and an intermediate hatchway 12 for the motor unit (not shown). The center of gravity of the machine is designated C. G. in Fig. 1. That portion of the hull to the rear of the point C. G. will be hereinafter referred to as the after-body 13 as distinguished from the forebody 10. The after-body 13 is provided with a cockpit 14 for the pilot.

Lateral fins or excrescences 15 augment the hydroplaning area of the hull, strengthen it longitudinally, and materially increase its displacement. These fins 15 emanate from the extreme bow and terminate at the extreme stern, widening gradually as they approach an imaginary line passing trans-

versely through the hull at the point C. G. The fins also increase in depth from the bow end to a point substantially amidships so that the point of maximum displacement lies 5 at or near the mentioned imaginary line. From this line the depth of the fins decreases gradually toward the stern although with less prominence.

The fins are preferably constructed as an 10 integral part of the hull or body (although they may be made separately water tight) because of the added strength which is possible when thus made. The interior frame work can be extended out uninterrupted 15 from the keel line to the lateral margins of the fins. By giving the fins depth at their lateral margins the hull displacement is increased and the fins made stronger. This added depth is advantageous in that a sub- 20 stantially vertical surface is provided at the chines, whereby immersion of the fins, due to side winds, is prevented.

The bottom of the hull is characterized 25 by convexity both longitudinally and trans- versely and is of acute V-form in trans- verse section throughout its full length. At the bow end of the hull the bottom is more acutely V-formed than at the rear end be- cause of the advantage derived as a result 30 of such construction. The bow end of the bottom thus partakes of both a scow and cut-water form. Figs. 1, 2 and 3 illustrate these characteristics particularly well.

While hydroplaning, only the fore part 35 of the bottom surface serves as a hydro- planing surface. The upward inclination of the after part of the bottom surface pre- vents its use in this capacity. The drag or resistance however which the after portion 40 of the hull bottom would naturally offer is minimized by the two step construction. The forward step, designated 16, lies ap- proximately beneath the center of gravity and the rear step 17, intermediate the step 45 16 and the stern. Were the second step omitted there is a possibility that the skin friction and suction would be so great as to prevent breaking away from the water surface while hydroplaning. The hydro- 50 planing surface of the hull is designated as an entirety by the numeral 18.

The inferior frame-work of the hull in- 55 cludes a keel 19 which extends substantially the full length of the hull. At its forward end it extends upwardly on an easy curve to a point at the extreme bow end of the hull where it is reversely curved to extend back for a short distance so that it functions throughout such portion of its length 60 as a deck stringer. Floors 20 extend out right and left from the keel 19 to provide a foundation for the bottom planking 21. These floors are substantially uniformly spaced and are fastened at their extremities 65 to chine stringers 22 co-extensive with the

bottom outside marginal edges of the fins. Intermediately the floors 20 are supported by engine bed beams 23 of a construction such that they not only function as motor supports but also as intimate structural ele- 70 ments of the hull. These engine bed beams 23 extend substantially the full length of the hull and comprise vertically separated beam sections 24 and 25 having post con- nections 26. The upper beam section 24 is 75 substantially straight throughout its full length while the lower beam section 25 is bowed so that at or near its ends it intersects the upper beam section 24. Fittings 27 are provided at stations along the beams 24 and 25 to receive the ends of the posts 26 and at the same time provide anchorages 80 for wires 28 cross arranged between the beam sections to effectually brace them (see Figs. 4 and 5). The floors 20 are 85 notched to receive the lower beam sections 25 of the motor supports (see Fig. 6). This not only strengthens the floors but gives the supports themselves a good solid 90 foundation. This arrangement and con- struction of the motor supports is such that the vibrational strains of the motor which is mounted directly upon them are distributed uniformly throughout the full 95 length of the hull. Landing and hydro- planing strains are also effectually distrib- 100 uted as a result of this arrangement.

Fin frames 29 are provided at the outer marginal edges of the fins. These frames interconnect the chine stringers 22 and 100 stringers 30 located at the top outside marginal edges of the fins. It will be noted that these frames 29 are of a size approximately equal to the floors 20 that added strength at the fin edges may be provided. Frames 105 31 together with stringers 32, seam bat- tens 33 and bearers 34 constitute the re- maining elements of the interior hull frame-work. The bearers 34 like the en- gine bed beams 23 serve a two fold purpose. They not only afford a foundation for the floors 20 but they support the weight of 110 the wing structure which is mounted di- rectly upon them. Each bearer comprises a beam section 35, a beam section 36, verti- cally extending posts 37 and diagonal 115 braces 38. The braces extend forwardly and downwardly from the upper beam sec- tion 35 and like the posts 37 interconnect the beam sections in such a manner that the sections constitute in effect a vertically lat- ticed beam. Appropriate fittings 39 are 120 provided at the extremities of the posts 37.

The lower beam sections 36 of the bear- 125 ers 34 are curved longitudinally and extend for the greater portion of the length of the hull. They are connected at their for- ward extremities to the keel at its extreme forward end. The upper beam sections 35 are not so extended. While they are con- 130

5 nected with the keel 19 at its extreme rear-
ward end they terminate forwardly at a
point somewhat in advance of the imagi-
nary line intersecting the point C. G.
10 Througout their length they are rear-
wardly and downwardly inclined from
their forward end to function not only as
wing structure supports but also as rails
upon which the wing structure slides back
15 when shed as a unit with the false decking
40 provided at the after end of the hull.
The sheddable feature of the craft is de-
scribed at length in a co-pending applica-
tion Serial No. 222,212, filed concurrently
herewith.

Although the wing structure forms no
part of the hull *per se* it will be noted that
the beams of the wing rest directly upon the
rails or upper beams of the bearers and
20 that these beams, if released, are free to
slide back until shed clear of the hull since
the rails are free from obstruction through-
out.

25 Intermediately and at various points
throughout its length the hull is divided
transversely by a number of water tight
bulkheads 42 of varying heights according
to location. The bulkheads not only trans-
30 versely brace the hull but by reason of their
continuation laterally to the fin edges they
transversely brace the fins. Moreover, they
act as stiffeners for the engine bed supports
and for the bearers. The break provided in
35 the hull bottom near its stern end (see Fig.
5) is for a water propeller and water rudder
(not shown). It is intended that the water
rudder and propeller be withdrawn into an
appropriate housing when the craft is used
40 for aerial flight. As this does not however
constitute part of the invention herein set
forth further description will be foregone.

Another feature which is emphasized is
the relation between the wing structure and
the motor together with its support. The
45 upper beam-sections of the bearers 34 are
tied down by good stiff wires 43 to the lower-
sections of the motor supports at points di-
rectly beneath each wing beam. In this way
the lift strains of the wing structure are car-
50 ried deep into the hull and distributed over
substantially its full length. Furthermore
the weight of the motor itself acts directly
against such strains so that the hull in its
entirety is constituted a correlated whole.
55 The details of the fastening devices or fit-
tings whereby the wing beams are held in
place are immaterial. It is sufficient to say
that the wires 43 are anchored to these fit-
tings at one end and to the fittings 27 at the
60 other. These latter fittings, as specified, are
placed directly beneath the vertical posts of
the engine supports.

Although we have described a more or less
precise embodiment of the invention it is to
65 be understood that no limitations other than

imposed by the claims are intended to be
made.

What is claimed is:

1. A hull for flying boats having lateral
fin excrescences of gradually increasing 70
width from the opposite ends of the hull,
the length of the excrescences being such
that they extend substantially throughout
the full length of the hull and at their ex-
tremities merge into the hull without a sub- 75
stantial break in its continuity.

2. A hull for flying boats having fin ex-
crescences of gradually increasing depth at
their outer margins from the bow end of the
hull to a point substantially amidships, from 80
which point the fins at said outer margins
gradually decrease in depth as they continue
toward the stern.

3. A hull for flying boats having lateral
fin excrescences of gradually increasing 85
depth at their outer margin from the bow
end of the hull, the depth of the fins at the
amidships portion of the hull being greater
than the depth rearwardly of said point, the
decrease in depth being gradual from said 90
amidships portion aft.

4. A hull for flying boats including lon-
gitudinal stringers having longitudinal sali-
ent bottom edges and straight top edges,
the arrangement of the stringers being such 95
that the bottom edges thereof directly con-
tact the framework of the hull bottom
while the top edges directly support the
power plant for the boat.

5. A hull for flying boats including floors 100
which provide a foundation for the hull bot-
tom, together with longitudinal stringers of
a construction such that they directly con-
tact a plural number of the floors, said
stringers transversely of the hull being 105
spaced apart a distance equal to the space
between the supporting elements of the
power plant whereby the latter may rest
directly upon said stringers.

6. A hull for flying boats including 110
stringers as structural elements of the boat
framework, the depth of the stringers be-
ing such that they not only strengthen the
hull longitudinally throughout a substantial
portion of its length by contact with the 115
bottom framework thereof, but conjointly
function as supports for the power plant,
said stringers being transversely spaced a
distance equal to the space between the sup-
porting element of the power plant. 120

7. A hull for flying boats, including
stringers as structural elements of the hull
framework, each stringer comprising a plu-
ral number of sections arranged one above
the other, the lowermost sections being in 125
direct contact with the floors of the hull bot-
tom and connected with the uppermost sec-
tions, the construction of the uppermost sec-
tions being such that they engage beneath
and directly function as motor unit supports. 130

8. A hull for flying boats including bearers of a construction such that they extend longitudinally of the hull throughout the greater portion of its length, the bottom 5 edges of the bearers being in direct contact with the floors of the hull bottom and the top edges in direct contact with elements of the wing structure.

9. A hull for flying boats including bearers as structural elements of the hull framework, each bearer comprising a plural number of sections arranged one above the other, the placement of the lowermost sections being such that they are in direct contact with 15 the floors of the hull bottom, the placement of the uppermost sections being such that they afford a support for the wing structure of the craft, said sections being directly interconnected by diagonally extending braces 20 and vertically extending posts.

10. A hull for flying boats including bearers as structural elements of the hull framework, each bearer comprising a plural number of sections arranged one above the other, 25 the bottom edges of the lowermost sections being in direct contact with the floors of the hull bottom, the top edges of the uppermost

sections being in direct contact with the structural elements of the wing structure, said uppermost sections being rearwardly 30 and downwardly inclined from their forward ends, the bearers themselves being arranged respectively in the approximate vertical plane of the opposite sides of the hull.

11. A hull for flying boats including bearers and longitudinal stringers as structural elements of the hull framework, the bottom edges of the bearers being in direct contact with the framework of the hull bottom and the top edges in direct contact with structural elements of the airplane wings, and the bottom edges of the longitudinal stringers likewise in direct contact with the bottom framework, the top edges of said stringers affording supports for the power plant, the 45 stringers being spaced apart a distance equal to the space between the supporting elements of the power plant and the bearers spaced apart a distance equal to the width of the hull. 50

In testimony whereof we hereunto affix our signatures.

GLENN H. CURTISS.
WILLIAM L. GILMORE.
